UNITED STATES PATENT OFFICE.

JOHN P. EUSTIS, OF NEWTON, MASSACHUSETTS.

DESIGN FOR A TEA-STRAINER.

SPECIFICATION forming part of Design No. 29,058, dated July 19, 1898.

Application filed February 28, 1898. Serial No. 672,105. Term of patent 7 years.

To all whom it may concern:

Be it known that I, JOHN P. EUSTIS, a citizen of the United States, residing at Newton, in the county of Middlesex and State of Massachusetts, have invented a new and original Design for a Tea-Strainer, of which the following is a specification.

Reference being had to the accompanying drawings, Figure 1 is a top plan view, and Fig. 2 a sectional view on line 2 2 of Fig. 1, of a tea-strainer having a drip-guard and spring-clip.

As shown in the drawings, the leading or material feature of my invention consists in the new, useful, and original shape or configuration of the tea-strainer as a whole, comprising the strainer proper, the drip-guard, and the spring-clip, A being the drip-guard, B the strainer, and D the clip. Drip-guard A is concavo-convex in cross-sectional contour and is attached at a' to the rear portion of the edge of the strainer, which is cup-shaped, the concave surface of the drip-guard being opposed to the rear and lower portion

b of the strainer, with a space b or settling-chamber between the opposed walls of the strainer and drip-guard. Spring-clip D is of wire bent to form the tongue d', extremities d² of which are secured to the rear portion of the brim of the strainer, the side portions d³ of the tongue projecting rearwardly of the strainer over and outwardly beyond the portions d⁴ of the clip to form the spout-receiving space d⁵ between the under side of the tongue and the upper side of the portions d⁴.

What I claim is—

The design for a strainer for tea, coffee and like pots, substantially as described.

In testimony whereof I have signed my name to this specification, in the presence of two subscribing witnesses, on this 18th day of February, A. D. 1898.

JOHN P. EUSTIS.

Witnesses:

EDWARD S. BEACH,
E. A. ALLEN.
